UNITED STATES PATENT OFFICE.

CHARLES E. HOOD, OF LYNN, MASSACHUSETTS, ASSIGNOR TO UNITED SHOE MANUFACTURING CORPORATION, OF PATERSON, NEW JERSEY, A CORPORATION OF NEW JERSEY.

WORK-POSITIONING DEVICE.

Application filed October 20, 1926. Serial No. 142,986.

This invention relates to work positioning devices and is herein illustrated as embodied in a gaging mechanism for locating a sole or a sole blank relatively to the operating instrumentalities of a skiving machine of the type disclosed in United States Letters Patent No. 1,382,689, granted June 28, 1921, in the name of W. C. Stewart.

Skiving machines of the type referred to are designed for shanking out shoe soles, i. e., for beveling the margins at the opposite sides of the shank portions of the soles. For this purpose each machine is provided with a die roll and a pressure roll which cooperate to feed a sole past a stationary skiving knife, the die roll being provided with sleeves, portions of which are shaped to form a matrix for determining the character of the cuts made by the skiving knife. In the use of machines of this type the forepart of a sole is introduced manually between the die and pressure rolls and the rear portion of the sole is laid upon a sole feeding carriage which is operated to initiate the feed of the sole. The sole is positioned longitudinally by means of a back gage on the sole feeding carriage so that, irrespective of the length of the sole, its ball line will always bear the same relation to the matrix. The sole is positioned laterally with respect to the matrix by two centering devices each comprising two gage fingers articulated for movements in unison through equal distances toward and from each other, one pair of fingers being mounted upon the frame of the machine and arranged to engage the opposite edges of the sole at the ball or widest portion of the forepart, and the other pair of gage fingers being mounted upon the sole feeding carriage and arranged to engage the opposite edges of the sole approximately at the heel breast line. To accomplish this longitudinal positioning of soles of different sizes without interfering with the lateral centering of the heel portions of the soles at the breast line, the back gage and the breast line centering device are made adjustable in unison relatively to the sole feeding carriage toward and from the matrix, and indexing mechanism is provided for effecting this adjustment. The range of adjustment of these gaging devices is sufficient to accommodate the entire range of sizes of soles for men's and women's shoes. No provision has been made hereto-

fore, however, for accommodating soles short enough to be used in children's shoes.

In view of the foregoing, it is one of the objects of the present invention to improve the means for centering the heel portions of the soles so as to provide for operation upon a larger range of sizes, including relatively short soles for use in children's shoes. In the illustrated embodiment of the invention this result has been obtained by mounting a second pair of gage fingers upon the sole feeding carriage for adjustment toward and from the matrix in unison with the back gage and the other heel centering fingers. To avoid the necessity of providing separate equalizing mechanism for each pair of heel centering fingers, both pairs of fingers have been mounted upon a single pair of carriers which are articulated for movements in unison to control the centering movements of all the heel centering fingers. The heel centering fingers of the second pair are made longer than the fingers of the first pair and are thereby adapted for use in connection with comparatively short soles such as those employed in the making of children's shoes. In order that the relatively long centering fingers shall not interfere with the normal operation of the short fingers and vice versa the fingers of each pair are mounted so that they may be moved out of operative position when the fingers of the other pair are being used. Provision is also made for locking the fingers of each pair in both operative and inoperative positions and if desired, the long fingers and the short fingers may be interconnected for movements simultaneously in opposite directions so that the fingers of neither pair can interfere with the actions of the fingers of the other pair.

The invention further consists in the features of construction and combinations and arrangements of parts hereinafter described and claimed.

In the accompanying drawings, Fig. 1 is a view, partially in plan and partially in section, of so much of a shanking-out machine as is necessary to illustrate the embodiment of the present invention therein;

Fig. 2 is a detailed sectional view taken along the line 2—2 of Fig. 1;

Fig. 3 is a perspective view of a portion of the mechanism shown in Fig. 1, illustrating particularly the mode of operation

of the improved breast line centering mechanism; and

Fig. 4 is a detailed view, partially in side elevation and partially in section, illustrating a modified construction of the breast line centering mechanism.

The invention is illustrated as embodied in a shanking-out machine of the type disclosed in Letters Patent No. 1,382,639, hereinbefore referred to. In the drawings, the die roll is indicated at 8, the matrix sleeves on the die roll at 10, the pressure or feed roll at 12, the skiving knife at 14, the sole feeding carriage at 16, the heel or back gage at 18, the back gage slide at 20, and the ball line or forepart centering gages at 22. The breast line or heel part centering gages are designated by the general reference numeral 24 and a portion of the indexing mechanism for adjusting the back gage and the breast line centering gages is indicated at 26 in Fig. 1. A sole blank, herein shown as a block sole S, is shown supported by the sole feeding carriage 16 with the ball portion of the blank extending between the die roll and the pressure roll, in readiness to be acted upon by the portions of the sleeves 10 which constitute the matrix. The sole blank is located lengthwise with reference to the matrix by means of the back gage 18 and is centered laterally relatively to the matrix by the gaging devices 22 and 24. The die and pressure rolls co-operate to feed the sole blank past the skiving knife while the matrix acts upon the opposite margins of the shank portion of the sole blank to offset these margins from the plane of the sole, thereby deflecting them into the plane of the skiving knife so that they will be reduced or beveled as the sole blank is fed past the knife. The knife cuts from the ball line toward the breast line. Therefore, to accommodate different sizes of the sole blanks the back gage is made adjustable toward and from the knife and indexing mechanism is provided whereby all soles, irrespective of size, may be initially located with the ball line in the same relation to the knife. The centering gages for the heel portion of the sole are made adjustable in unison with the back gage to insure that they will engage the edges of different sized sole blanks in substantially the same relation to the breast line. With the exception of the back gage 18 and the centering gages 24 for the heel portion of the sole blank, all the parts of the machine thus far mentioned are substantially the same in construction and arrangement and have substantially the same mode of operation as corresponding parts disclosed in the above-mentioned Letters Patent, and reference may be had to said patent for details of construction and operation not fully set forth herein.

As heretofore constructed shanking-out

machines of the general type just described have been adapted to operate upon soles for men's or women's shoes and the range of adjustment of the back gage and the breast line centering gages has not been sufficient to accommodate small soles such as those used in children's shoes. As herein illustrated, provision has been made for accommodating soles small enough to be used in children's shoes without interfering with or modifying the indexing mechanism for adjusting the back gage and the breast line gages toward and from the knife. To this end, the illustrated back gage is mounted with provision for an increased range of adjustment relatively to the slide upon which it is supported and improved means has been provided for centering the heel portion of the sole.

The increased range of adjustment of the back gage is attained by lengthening the slot 28 through which extends the screw 29 by means of which the back gage is secured to the back gage slide 20.

The improved means for centering the heel portion of the sole comprises two pairs of centering fingers 30, 30 and 32, 32, each pair being mounted upon carriers 34, 34, in the form of levers which are pivoted upon posts 36, 36 carried by the back gage slide 20. The carriers 34 are provided with arms which extend toward one another and carry gear segments 40 which intermesh so that the carrier (and the gage fingers respectively mounted thereon) will move in unison. One of the carriers 34 is acted upon by a tension spring 42 which is secured at one end to the carrier and at its opposite end to a pin 44 on the slide 20, and which tends to move the centering fingers inwardly. A stop screw 46 is mounted on the slide 20 and arranged to engage one of the carriers 34 so as to limit the inward or approaching movement of the gage fingers. By turning the screw 46 the gage fingers may be adjusted for operating upon different widths of soles so that a sole of a particular width may be inserted between the gage fingers of either pair without requiring excessive movement of the gage fingers.

As shown, the gage fingers 30 are comparatively short while the gage fingers 32 are comparatively long, the fingers 30 being adapted for use in connection with relatively long soles such as those used in men's and women's shoes while the fingers 32 are adapted for use in connection with relatively short soles such as are employed in children's shoes. In order that the short fingers 30 may be prevented from interfering with the normal and effective use of the long fingers 32 in the centering of short sole blanks, and in order that the long fingers 32 may be prevented from interfering with the proper use of the short fingers 30 in

centering of long sole blanks, and more particularly long block soles, the gage fingers of each pair are so mounted upon the respective carriers 34 that each pair of fingers 30 may be moved out of operative sole-engaging position when the other pair of fingers are being used. To this end, each finger 30 is pivoted at 48 between ears formed on the respective carrier 34 for up and down swinging movements at right angles to the in and out movements of the fingers in the performance of their centering functions. The gage fingers 32 are similarly pivoted, as indicated at 50, between ears on the carriers 34. In Fig. 3 the short fingers 30 are shown as being operatively positioned for engagement with the edges of a sole while the long fingers 32 are shown as having been swung upwardly into vertical inoperative positions, out of the plane of the sole, where they will not interfere with the proper functioning of the short fingers 30. When the long fingers 32 are swung downwardly into horizontal or operative positions, as shown by dotted lines in Fig. 3, for operation upon short soles, the short fingers 30 will be swung upwardly into vertical or inoperative positions. To hold each gage finger 30 in operative or inoperative position, as may be desired, a spring-pressed locking plunger 52 is carried by each of said fingers and is arranged to engage with one or the other of two holes 54 in a segment plate 56 formed on the respective carrier 34. Similarly, spring-pressed plungers 58, carried by the long gage fingers 32, serve by co-operation with holes 60 in segment plate 62 on the carriers 34, to lock the long gage fingers in either operative or inoperative positions. In using the above-described improved breast line centering mechanism, if a relatively long sole is to be operated upon, the short gage fingers 30 will be operatively positioned and the long gage fingers 32 will be swung into raised or inoperative positions, as shown by full lines in Fig. 3. To adapt the machine for operation upon relatively short soles it is only necessary to adjust the back gage toward the knife 14, to swing the long gage fingers downwardly into the horizontal or operative positions shown by dotted lines in Fig. 3, and to raise the short gage fingers 30 from horizontal to vertical positions where they cannot engage any portion of the sole blank (such for example as the rear corners of a block sole) so as to interfere in any way with the centering action of the long gage fingers. By providing a pair of long gage fingers and a pair of short gage fingers and mounting the long and short fingers of each pair upon the same carrier, as above described, the shanking-out machine has been adapted (by the employment of mechanism of a very simple character) for operation

upon a much wider range of sizes of sole blanks, and this adaptation of the machine has been effected without interfering with or modifying in any way the construction or mode of operation of the calibrated indexing mechanism for effecting the initial adjustment of the machine in accordance with the particular size of sole blanks to be operated upon.

Fig. 4 is illustrative of a breast line centering mechanism of modified construction wherein provision is made for facilitating proper adjustment of the long and short gage fingers and insuring that neither shall interfere with the effective operation of the other. For this purpose each of the long gage fingers 32 is connected with the respective short gage finger 30 by intermeshing gear segments, such as shown at 60 (Fig. 4), in such a manner that movement of either gage finger toward or from operative position will cause movement in the opposite direction of the other gage finger, thus insuring against any possible interference of either finger with the other and enabling adjustment of both fingers to be effected by the manual movement of one of them. As shown, the long gage finger 32 carries the spring-pressed locking plunger 58, already described, which is arranged to co-operate with holes in the segment plate 62 for locking the gage finger in either operative or inoperative position. Inasmuch as the long gage finger 32 is connected with the short gage finger 30 through the intermeshing gear segments 60, as above set forth, it will be appreciated that it will not be necessary to associate an additional locking plunger and co-operating segment plate with the short gage finger, since positive locking of both gage fingers in either operative or inoperative position is insured by the use of a single locking plunger and segment plate. By embodying this modified construction in the machine not only is the construction of the centering mechanism materially simplified but, as above mentioned, the selective adjustment of the long and short gage fingers is made easier and the interference of either gage finger with the action of the other is insured against.

The invention having been described, what I claim as new and desire to secure by Letters Patent of the United States is:

1. In a machine of the class described, movable gage fingers for locating sole blanks having certain characteristics, and other gage fingers movable in unison with said movable gage fingers for locating sole blanks having different characteristics from those acted upon by said movable fingers.
2. In a machine of the class described, articulated gage fingers for laterally centering the ends of long sole blanks, and other gage fingers carried by said articulated fin-

- gers for laterally centering the ends of short sole blanks.
3. In a machine for operating upon sole blanks, in combination, operating instrumentalities, a pair of movable gage fingers for centering the heel portions of long soles, a second pair of movable gage fingers for centering the heel portions of short soles, and a pair of carriers articulated for movements in unison to control the centering movements of both pairs of gage fingers.
4. In a machine for operating upon sole blanks, the combination with the operating instrumentalities, of a sole feeding carriage, a pair of movable gage fingers for centering the heel portions of long soles, a second pair of movable gage fingers for centering the heel portions of short soles, and a pair of carriers mounted upon said carriage and articulated for movements in unison to control the centering movements of both pairs of gage fingers.
5. In a machine for operating upon sole blanks, in combination, operating instrumentalities, a support adjustable toward and from the operating instrumentalities, a pair of movable gage fingers mounted on said support for centering the heel portions of long soles, a second pair of movable gage fingers mounted on said support for centering the heel portions of short soles, and means for causing the fingers of each pair to move in unison toward and from each other.
- 35 6. In a machine for operating upon sole blanks, in combination, operating instrumentalities, devices for operating upon the ends of soles of a particular range of sizes for centering the ends of the soles laterally with respect to the operating instrumentalities, devices for operating upon soles of a different range of sizes for centering the corresponding ends of the soles laterally with respect to the operating instrumentalities, and indexing mechanism for adjusting said centering devices in unison toward and from the operating instrumentalities.
7. In a machine for operating upon sole blanks, a gage mechanism comprising articulated centering fingers movable into and out of position for engaging the opposite edges of the heel portions of sole blanks of a certain range of sizes, and other centering fingers movable into and out of operative position for engaging corresponding portions of sole blanks of a different range of sizes.
8. In a machine for operating upon sole blanks, in combination, operating instrumentalities, a support over which a sole blank is moved into position to be operated upon, a pair of pivotally mounted carriers connected for movements in unison toward and from each other, relatively short gage fingers for engaging the opposite edges of long sole blanks severally mounted on said carriers, and relatively long gage fingers for engaging the corresponding portions of short sole blanks, said last-named fingers being severally mounted upon said carriers for movements into and out of the plane of a blank on said support.
9. In a machine for operating upon sole blanks, in combination, operating instrumentalities, a support over which a sole blank is moved into position to be operated upon, a pair of pivotally mounted carriers connected for movements in unison toward and from each other, relatively short gage fingers for engaging the opposite edges of long sole blanks severally mounted on said carriers, relatively long gage fingers for engaging the corresponding portions of short sole blanks severally mounted upon said carriers for movements into and out of the plane of a sole on said support, and means for locking said gage fingers in operative and inoperative positions.
10. In a skiving machine for shanking out sole blanks, in combination, a skiving knife, a pressure roll, a die roll with a matrix, means for supporting a blank to be fed lengthwise between the rolls, adjustable means for locating a sole blank lengthwise with respect to the matrix, centering gages movable toward and from each other in unison for engaging opposite edges at the heel end of a sole blank to center long blanks laterally with respect to the matrix, and auxiliary gages carried by said centering gages for centering short sole blanks laterally with respect to the matrix.
11. In a machine for operating upon sole blanks, the combination with the operating instrumentalities, of a support over which the sole blanks are moved into position to be operated upon, a pair of carriers articulated for movement in unison toward and from the path of the blanks, gage fingers severally mounted on said carriers for movements into and out of the plane of a blank on said support for laterally centering sole blanks of a certain range of sizes, and other gage fingers severally mounted upon said carriers for movements into and out of the plane of a blank on said support for laterally centering sole blanks of a different range of sizes.
12. In a machine for operating upon sole blanks, the combination with the operating instrumentalities, of a support over which the sole blanks are moved into position to be operated upon, a pair of carriers severally pivoted at opposite sides of the path of movement of the blanks for movements toward and from each other, connections between said carriers for causing them to move in unison, gage fingers severally pivoted on said carriers for movements into and out of the plane of the blanks for laterally centering blanks of a certain range of sizes,

other gage fingers severally mounted upon said carriers for movements into and out of the plane of the blanks for laterally centering blanks of a different range of sizes, and means for locking all of said gage fingers in both operative and inoperative positions.

13. In a machine for operating upon sole blanks, the combination with the operating instrumentalities, of means for locating both long and short sole blanks lengthwise with corresponding portions of the blanks bearing the same relation to the operating instrumentalities, a set of gage fingers for laterally centering the ends of long sole blanks, and another set of gage fingers for laterally centering the corresponding ends of short sole blanks, the gage fingers of both sets being movable into and out of operating positions so that the fingers of either set may be used selectively.

14. In a machine for operating upon sole blanks, the combination with the operating instrumentalities, of means for locating both long and short sole blanks lengthwise with corresponding portions of the blanks bearing the same relation to the operating instrumentalities, a set of gage fingers for laterally centering the ends of long sole blanks, and another set of gage fingers for laterally centering the corresponding ends of short sole blanks, all of said gage fingers being movable into and out of operating positions and being interconnected to insure that when either set of fingers is operatively positioned the other set will be inoperatively positioned.

15. In a machine for operating upon sole blanks, the combination with the operating instrumentalities and means for locating long and short sole blanks with corresponding portions in same relation to the operating instrumentalities, of two sets of gage fingers, one set for laterally centering the ends of long sole blanks and the other set for laterally centering the corresponding ends of short sole blanks, the fingers of one of said sets being mounted to be moved out

of work engaging position to avoid interference with the operation of the fingers of the other set.

16. In a machine for operating upon sole blanks, in combination, operating instrumentalities, a support over which a sole blank is moved into position to be operated upon, a pair of pivotally mounted carriers connected to move in unison toward and from each other, a pair of primary gage fingers severally pivoted on said carriers for movements into and out of the plane of the blank for laterally centering the blank with respect to the operating instrumentalities, a pair of secondary gage fingers severally pivoted on said carriers for movements into and out of the plane of the blank for laterally centering the blank, and connections between each primary finger and each secondary finger for causing the main and secondary fingers to move simultaneously in opposite directions.

17. In a machine for operating upon sole blanks, in combination, operating instrumentalities, a support over which a sole blank is moved into position to be operated upon, a pair of pivotally mounted carriers connected to move in unison toward and from each other, a pair of primary gage fingers severally pivoted on said carriers for movements into and out of the plane of the blank for laterally centering the blank with respect to the operating instrumentalities, a pair of secondary gage fingers severally pivoted on said carriers for movements into and out of the plane of the blank for laterally centering the blank, connections between each primary finger and each secondary finger for causing the main and secondary fingers to move simultaneously in opposite directions, and a single device for locking both the primary and the secondary gage fingers in operative and in inoperative positions.

In testimony whereof I have signed my name to this specification.

CHARLES E. HOOD.
